UNITED STATES PATENT OFFICE.

ARTHUR LEE LIGON, OF FORT STOCKTON, TEXAS.

PUMP.

1,223,498.

Specification of Letters Patent. Patented Apr. 24, 1917.

Application filed June 5, 1916. Serial No. 101,722.

To all whom it may concern:

Be it known that I, ARTHUR L. LIGON, a citizen of the United States, residing at Fort Stockton, in the county of Pecos and 5 State of Texas, have invented certain new and useful Improvements in Pumps, of which the following is a specification.

My invention has relation to an improvement in deep well pumps of particularly 10 that type or class wherein the well casing for the relatively deep well is formed of detachable sections and the pump barrel, pump, sucker rod and accessories all are arranged to be readily removed from the 15 well casing for the purpose of repairs or renewal of parts, and in such connection it relates to provision of means whereby the pump barrel may be securely locked to position in the well casing during the operation 20 of the pump and yet readily released from said casing when the pump parts and barrel are to be removed from said casing.

In deep well pumps whether for water or oil the casing of the well is formed of a 25 plurality of sections united together by coupling sleeves or collars. These sections and their couplings should be so arranged as to permit of the ready insertion of the pump barrel, plunger and auxiliary parts into the 30 casing after said casing is placed in position in the well and also to permit of the withdrawal of said pump barrel and pump parts without withdrawing or disturbing the casing.

Heretofore such construction of casing, 35 pump barrel and pump have been attempted but so far as I am aware there has been no simple and efficient means for locking the pump barrel with its lower valve in proper 40 position in the casing, such locking means maintaining the barrel and lower valve in such proper position during the working of the pump.

While the main object of my present invention is to provide such simple and efficient 45 means for so locking the pump barrel in proper position in the casing, an equally important object of the invention is to provide a means whereby during an erratic stroke 50 of the pump plunger or piston in the barrel, said barrel will not be disengaged or shifted out of its proper position but the excess of stroke will be taken up and automatically remedied without however preventing the

removal of the barrel should such removal 55 become necessary or desirable.

Secondary objects of my invention are to provide improved constructions and arrangements of the two valves, one carried by the sucker rod and the other by the barrel and 60 to provide means carried by the sucker rod to coöperate with a sleeve and spring in normally holding the barrel to position and to take up for the excess in upward or downward stroke of the plunger without a lifting or lowering of the pump barrel.

The nature and scope of my invention will be more fully understood from the following description taken in connection with the accompanying drawings forming a part 70 hereof, in which—

Figure 1, is a vertical sectional view of a deep well pump embodying the main features of my invention.

Fig. 2, is an enlarged view of the upper 75 portion of Fig. 1.

Fig. 3, is an enlarged view of the lower portion of Fig. 1.

Fig. 4, is a view partly in section but showing the piston head and lower valve in 80 elevation.

Fig. 5, is an elevational view partly broken away illustrating the pump and well casing.

Figs. 6, 7 and 8 are cross-sectional views taken respectively on the lines 6—6; 7—7; 85 and 8—8 of Fig. 2.

Fig. 9, is a cross-sectional view taken on the line 9—9 of Fig. 3.

Referring to the drawings the well casing is formed of a series of sections of which 90 1, incloses and supports the pump barrel 2, the lower end of section 1 is connected with the next lower section by a coupling 3 which internally is inverted frusto-conical in shape to form a valve seat 4 for the valve 5 carried by the lower end of the pump barrel 2. The upper end of section 1 is connected to a next preceding section of the casing by a coupling 6 having an interior diameter slightly larger than the exterior diameter of 95 the pump barrel 2. The construction and arrangement of the lower valve 5 are illustrated in detail in Figs. 1, 3 and 4 and form a part of this present invention in that the valve can be readily assembled, removed and 100 disassembled for the purpose of repairs and yet accurately seat itself in the casing coupling 3 when the pump barrel 2 is in position.

- tion. Specifically considered the valve 5 consists of a tubular piece 7 closed at its upper end by a ball 8 and screw threaded in collar 9 carrying the cage 10 for said ball 8.
- 5 The lower end of the tubular piece 7 is laterally and transversely slotted as at 11 to permit of the insertion of a suitable key or tool and of the turning of the tube 7 to remove it from the collar 9. On the exterior of tubular piece 7 is arranged a series of tapered packing rings 12 which when in position constitutes a conical or frusto-conical exterior fitting snugly the frusto-conical interior of coupling 3. The collar 9 has its lower edge provided with a key seat or slot 13 so that said collar 9 may be advanced or retracted by screw threaded engagement with or out of the interior of the lower end of the pump barrel 2.
- 10 The piston 14 working in barrel 2 comprises a tubular body 15 having its upper end closed by a ball 16 held in cage 17 which cage is screw threaded to the upper end of said body 15. On the exterior of body 15 is arranged alternate washers or packing rings 18 and clamping sleeves 19, the whole structure being held in place by the lower sleeve 19^a, screw threaded on the exterior of the lower end of tubular body 15. This lower sleeve 19^a has its lower edge slotted as at 20 to permit of the use of a tool in advancing or retracting the sleeve 19^a on the tubular body 15. The cage 17 is screw threaded to the lower end of the lowest section 21 of the sucker rod.
- 15 The means for properly supporting the pump barrel 2 so that its lower valve 5 shall be seated in the seat 4 formed by coupling 3 during the operation of pumping and the means for locking the barrel in prescribed position will now be explained.
- 20 The top of the barrel 2 is screw threaded to and carried by a tubular head 22 provided between its exterior and the interior of coupling 6 in which it fits, with packing rings or washers 23 and 24 arranged respectively near the lower and the upper end of the coupling 6. These packing rings 23, 24 serve as mudguards or means for preventing sand and dirt entering between the barrel 2 and casing section 1. It is obvious that if such means were not provided the gradual accumulation of sand and dirt in the space between barrel and casing would soon pack hard and act as a grouting or cement to prevent removal of the barrel from the casing if it were desirable to remove the barrel.
- 25 The tubular head 22 is locked to the coupling 6 by locking fingers 25 having enlarged ends 26 entering recesses 27 in the interior of coupling 6. These fingers 25 are spring fingers and can move or bend upward upon their fastenings 28, at the upper end of the fingers, to withdraw the enlarged ends 26 from said slots or recesses 27. To permit of

this inward bending of fingers 25 at the proper time, the head 22 is vertically slotted from a point below the point of fastening 28 to a point below the enlarged ends 26.

It is apparent from the foregoing description that when the head 22 attached to barrel 2 is pushed into place and locked to the coupling 6, the normal action of piston or plunger 14 in said barrel proceeds without disturbing the relation of the head 22 or the lower valve 5 in their respective seats or supports. However, an unusual or erratic stroke of the pump might cause piston 14 to strike the lower end of head 22 and thus lift said head out of locking engagement with coupling 6 and so elevate barrel 2 and lower valve 5 from the lower seat 4 in coupling 3. To prevent such accidental displacement of barrel 2 and head 22 I provide a means for taking up this erratic movement of the piston. In its simplest form this take-up mechanism comprises a tube 30 sliding in and closely fitting the tubular head 26, said tube 30 being held downward in said head 22 preferably by a spring 31 coiled around the exterior of the lower portion of the tube 30 and interposed between the flange 32 on the lower end of the tube 30 and the shoulder 33 of head 22 to which barrel 2 is screw threaded.

This tube 30 has midway of its ends a conical enlargement 34 on its exterior which when the parts are all properly assembled come opposite the enlarged ends 26 of fingers 25 and serve to lock said fingers in the recesses 27 of coupling 6. If now the plunger 14 raises above its usual stroke, the excess movement of the piston is taken up by the spring-controlled tube 30 and ordinarily when the piston descends, the spring 31 of tube 30 will force the tube down into its normal position to lock fingers 25 in the coupling 6. Should for any reason the spring 31 fail to act properly, the sucker or piston rod 21 is provided with preferably a star shaped collar 35 adapted to strike upon the upper edge of tube 30 and force said tube downward as the plunger 14 descends.

While I have described the sections 1 as a well casing it should be understood that said sections may constitute a pump tube for use within well casings already installed.

Having thus described the nature and objects of my invention what I claim as new and desire to secure by Letters Patent, is—

1. In a pump, a section of well casing, a pump barrel inclosed in said section, a tubular head in screw threaded engagement with the upper end of said barrel, a coupling connecting the section of casing with the next preceding section of casing, a means for detachably locking the head to the coupling, a piston traversing the barrel, and a take-up means traversing the head and entering the barrel, said takeup means arranged in the

path of the piston to receive the upward thrust of said piston and thereby prevent accidental displacement of the head in said coupling.

- 5 2. In a pump, a section of well casing, a coupling connecting said section with the next preceding section, a tubular head arranged within said coupling, a packing interposed between the head and coupling, a 10 lower coupling provided with a valve seat arranged on said section, and a pump barrel detachably connected to and supported by the head, said barrel provided with a lower valve entering and supported by the valve 15 seat of the lower coupling in connection with a piston traversing the barrel, a tube extending through the head into the barrel, a means for locking the head to the upper coupling, said tube constituting a means for holding the locking means for the head in place, and a spring interposed between the lower end of the head and the lower end of 20 the tube, said spring arranged to project the

tube downward in the head in the path of the piston to prevent said piston from directly engaging said head. 25

3. In a pump, a section of well casing, a pump barrel inclosed by said section, a tubular head detachably engaged with the upper end of said barrel, a coupling connecting 30 said section with a next preceding section of casing, a means for detachably locking the head to the coupling, a piston traversing the barrel, a piston rod traversing the head, a takeup means under spring tension traversing the head and extending into the barrel in the path of said piston to receive the upward thrust of said piston and prevent the piston striking said head, and a collar on the piston rod adapted to strike the takeup 35 means to return said means to its normal position after being moved by said piston. 40

In testimony whereof I have signed my name to this specification.

ARTHUR LEE LIGON.
